US0D1016853S

(12) **United States Design Patent** (10) Patent No.: **US D1,016,853 S**
(45) Date of Patent: ** Mar. 5, 2024

(54) **DISPLAY SCREEN OR PORTION THEREOF WITH GRAPHICAL USER INTERFACE**

(71) Applicant: **Apple Inc.**, Cupertino, CA (US)

(72) Inventors: **Lee Broughton**, Santa Cruz, CA (US); **Gary Butcher**, Los Gatos, CA (US); **Kevin Will Chen**, Cupertino, CA (US); **Nathan De Vries**, San Francisco, CA (US); **Christopher Foss**, San Francisco, CA (US); **Aled Williams**, Llandeilo (GB); **Christopher Wilson**, San Francisco, CA (US)

(73) Assignee: **Apple Inc.**, Cupertino, CA (US)

(**) Term: **15 Years**

(21) Appl. No.: **29/881,965**

(22) Filed: **Jan. 9, 2023**

CLAIM

The ornamental design for a display screen or portion thereof with graphical user interface, as shown and described.

DESCRIPTION

The FIGURE is a front view of a display screen or portion thereof with graphical user interface showing the claimed design.

The outermost broken lines in the FIGURE show a display screen or portion thereof, and form no part of the claimed design. The other broken lines in the FIGURE show portions of the graphical user interface that form no part of the claimed design.

1 Claim, 1 Drawing Sheet

Related U.S. Application Data

Oct. 30, 2017, now Pat. No. Des. 876,456, which is a continuation of application No. 29/567,734, filed on Jun. 11, 2016, now Pat. No. Des. 801,365.
